UNITED STATES PATENT OFFICE.

EDWARD H. FRICKEY, OF ST. LOUIS, MISSOURI, ASSIGNEE TO DIXIE MACHINERY
MANUFACTURING COMPANY, OF ST. LOUIS, MISSOURI, A CORPORATION OF MIS-
SOURI.

CRUSHER.

Application filed October 15, 1920. Serial No. 417,158.

To all whom it may concern:

Be it known that I, EDWARD H. FRICKEY, a citizen of the United States, and resident of St. Louis, Missouri, have invented certain new and useful Improvements in Crushers, of which the following is a specification.

This invention relates to improvements in crushers, and has for its object an outer 10 casing in which is axially mounted a hammer head provided with a plurality of pivotally mounted hammers, a hingedly mounted crusher head and a means for adjusting the position of the crusher head from the 15 exterior of the machine frame.

The essential feature of my invention in this construction of crusher is to provide an improvement in the method of adjusting a hingedly mounted crusher head so arranged that it may be brought in the peripheral radius of the rotating hammers.

Figure 1, is a side elevation of my invention.

Fig. 2, is a central sectional view of the 25 same.

Fig. 3, is a rear view of the machine.

Fig. 4, is a rear perspective view of one of the adjusting members made use of for manipulating the crusher head.

Fig. 5, is a rear sectional view of a part of the hammer head and the hammers carried thereby.

In the general structure of my invention I provide a suitable frame or housing 6 35 consisting of side walls 7 and 8, a front wall 9, a back wall 10, a top 11 and on the top is located a hopper 12 through which the material is fed into the machine.

Through the side walls 7 and 8 is placed 40 a shaft 13, this shaft is supported in suitable bearings 14 and on one end of the shaft is a driving pulley 15 and on the other end a fly wheel or like device 16.

On the shaft and inside the casing is 45 keyed a hammer head 17 which is provided with a plurality of circumferential grooves 18 and in these grooves are hingedly supported hammers 19, these hammers are held in hinged position by means of pins 20 50 extending through apertures 21 formed in the head, and these apertures are arranged at suitable intervals apart and each located a slight increased distance away from the center so that the heads can be adjusted 55 from aperture to aperture as the contacting

surface 22 becomes worn by steady contact with the material to be crushed.

The rear wall is provided with a suitable opening 23 which accommodates the insertion of the crusher head 24. This crusher head is constructed of a suitable frame consisting of a plurality of re-inforcing or strengthening ribs 25, all of them being connected by an integral plate 26, and on this plate is located detachable contact blocks 27 60 and against these blocks the material to be crushed contacts and these blocks are so arranged that during continuous use should the same become worn to such degree that it is necessary to replace the blocks they 65 can be removed and new ones replaced.

Through the ribs 25 is placed a supporting or hinged shaft 28, this shaft also passes through the side walls 7 and 8 of the frame and holds the crusher head in hinged position in the opening 23. The ribs are also provided near the bottom end with elongated openings 29 and in the walls 7 and 8, and in alignment with the openings 29 is formed elongated openings 30, these openings are shown by dotted lines in Fig. 2. Through the openings 29 and 30 is placed a shaft 31 and on the ends of the shaft and on the outside of the side walls 7 and 8 is attached the adjusting rods 32, these rods 65 consist preferably of a rounded shank 33 having its end provided with screw-threads 34, the opposite end is flattened as that indicated by the numeral 35 and provided with perforations 36 which fit over the projecting end of the shaft 31. These adjusting rods are held in position by the nuts 37 and the round shank 33 is supported in and passed through openings formed in the side frame 38 and the adjustment of the 70 head is controlled by the manipulation of the nuts 39 located on the screw-threaded end 34 of the shank.

By the use of the adjustable rods the 75 hingedly mounted crusher head can be readily and easily adjusted so as to regulate the grade of crushing, and also to take up the wear of the blocks carried by the head, and by this arrangement the position of the crusher head with the peripheral radius of 80 the hammers or pounders can be so positioned as to accommodate both the wearing of the head as well as the contacting ends of the hammers.

In this invention the essential feature is 85

The adjustable crusher head so arranged as to be adjusted from the outside of the machine thus avoiding the necessity of stopping the operation of the machine during 5 its adjustment.

Having fully described my invention what I claim is:

1. A crusher of the character described, comprising a housing having side walls and side frames therefor, a hingedly mounted crusher head supported in said housing, reinforcing ribs at the rear thereof having elongated slots therein, a shaft mounted in said elongated opening and passing through correspondingly elongated openings in said side walls, and adjusting bars associated with said shaft and adapted for longitudinal movement, said adjusting bars being mounted on the outside of said housing and having one of the ends threaded, and a nut on said threaded ends and coacting with said side frame, whereby the longitudinal movement of said adjusting bars is controlled.

5. 2. A crusher of the character described,

comprising a housing having side walls and side frames therefor, a hingedly mounted crusher head supported in said housing, reinforcing ribs at the rear thereof having elongated slots therein, a shaft mounted in said elongated opening and passing through correspondingly elongated openings in said side walls, and adjusting bars associated 26 with said shaft and adapted for longitudinal movement, said adjusting bars being mounted on the outside of said housing and having one of the ends threaded, and a nut on 30 said threaded ends and coacting with said side frame, whereby the longitudinal movement of said adjusting bars is controlled.

In testimony whereof, I have signed my name to this specification, in presence of two subscribing witnesses.

EDWARD H. FRICKEY.
